(57) **CLAIM**

The ornamental design for a cupping device, as shown and described.

DESCRIPTION

FIG. 1 is a bottom, front perspective view of a cupping device;

FIG. 2 is a front view thereof, the rear view being a mirror image;

FIG. 3 is right side view thereof, the left side being a mirror image;

FIG. 4 is a top view thereof;

FIG. 5 is a bottom view thereof; and,

FIG. 6 is a perspective view of the cupping device of FIG. 1 in use on a leg.

The broken lines of the cupping device represent unclaimed features of the article to which the design is applied. The partial human figure shown in broken lines in FIG. 6 is environmental subject matter intended to help illustrate how the claimed design appears when used and forms no part of the claimed design.
